Theodore H. Troller, Akron, Ohio

Application June 16, 1936, Serial No. 85,472

13 Claims. (Cl. 170—172)

This invention relates to propellers, and more especially it relates to rotary propellers or air-screws comprising two or more blades such as may be used, for example, for propelling vehicles 5 or for creating a velocity head of air, as in blowers and pumps.

Propellers of the character mentioned have blades that are cambered on one or both sides and provided with a rounded nose or leading edge. Such blades, as heretofore constructed, required to have a definite minimum area for a determinate load, and there were definite limits to the maximum load that the blades could exercise in an efficient manner. The aforesaid limitations of prior propeller blades reduces their usefulness in many ways and it is to the improvement of these conditions that the present invention is directed.

The chief objects of the invention are to provide an improved propeller blade capable of greater unit-area load than obtained in propeller blades heretofore provided; to provide an improved propeller blade that will permit reduced speed of rotation of the propeller without sacrifice of the efficiency thereof; to reduce the noise incidental to the operation of the propeller; to provide a propeller blade design that permits the blade to be made in narrower width and greater thickness, thus providing greater strength and resulting in less vibration while rotating; and to provide a propeller having a wider useful range of velocities. Other objects will be manifest as the specification proceeds.

It is well known that the specific load on propeller blades of the character mentioned can be materially increased if the layer of fluid (air) immediately adjacent a particular region of the surface of the rotating blade is energized or is removed therefrom. It has been proposed heretofore to accomplish this result by the use of suction for removing fluid from the said surface of the blade, and, alternatively, by the use of fluid pressure for energizing or breaking up the layer of air on the said surface of the blade, in either case the amount of fluid removed from the blade or ejected therefrom being relatively small as compared to the amount of fluid influenced by the rotary motion of the propeller.

To effect the movements of fluid as described it has been proposed to provide the propeller blades with ducts that extend to the axis of rotation in the hub of the propeller, through the latter, and connect with a suitable source of suction or fluid pressure, such as a suction or blower fan. Such

mechanism is expensive, complicated and frequently out of order.

In the present invention the forces set up by the rotation of the propeller blades are utilized for effecting a movement or flow of air in ducts 5 in the said blades as a means for sucking air from the surface of the blades and/or ejecting it therefrom. The invention also contemplates the controlling of the flow of air in the ducts in the blades, and the taking in and discharging of 10 air from the ducts without essential loss of power.

Of the illustrative embodiments of the invention shown in the accompanying drawing,

Figure 1 is a side elevation of a propeller constituting one embodiment of the invention, one 15 of the blades thereof being shown in transverse section;

Figure 2 and Figure 3 are side elevations of propeller blades showing other embodiments of 20 the invention;

Figure 4 is a side elevation of a propeller blade showing another embodiment of the invention, including an automatic control for fluid in the duct in the blade;

Figure 5 is a section taken on the line 5—5 of 25 Figure 4;

Figure 6 is a fragmentary elevation of a propeller constituting the invention including means for manually controlling the flow of fluid in the duct in a blade; and

Fig. 7 is a section taken on the line 7—7 of 30 Figure 6.

Referring to the drawing, in Figure 1 thereof is shown a propeller of the type used in air pumps and blowers, said propeller comprising a hub portion 10 and a plurality of radially extending blades 11, 11. The latter are of the type that have the major portion of their length, at least, of aerofoil section, that is, they have a blunt nose or leading edge, a cambered upper or suction face, 35 and a lower or pressure face of lesser camber, said faces meeting in a relatively thin, sharp, trailing edge. The blades 11 are made of metal, wood or Bakelite and are so shaped that their pitch is smaller adjacent their tips than near the hub, 40 and the blades so shaped as to enable easy fastening and adjustment in the hub, and providing a gradual transition from the region of aerofoil section to the portion that is mounted in the hub.

Formed interiorly of each blade 11 is a passage 50 or duct 13 that is disposed longitudinally of the blade and radially of the hub 10, the ends of said duct terminating in respective slots 14, 15 in the upper or suction face of the aerofoil portion of the blade. The slot 15 is disposed relatively near

- the tip of the blade and constitutes the delivery orifice of the duct 13. The slot 14 is disposed relatively near the hub 10 of the propeller and constitutes the intake orifice of the said duct. 5 The said slots are of relatively small area and do not materially reduce the effective area of the blade.

The propeller rotates in the direction indicated by the arrow, and by reason of such rotation the 10 centrifugal force set up in the air in ducts 13 of the propeller blades causes said air to move radially outwardly with relation to hub 10, with the result that said air is forcibly ejected from the slots 15 of the blades and concurrently air 15 is drawn into the ducts, through slots 14, by the resulting suction. Another factor that contributes to the aforesaid result is the differential fluid pressures that obtain on the suction side of the blade longitudinally thereof. Because the 20 speed of the propeller blade is greater at its tip than at its hub, the suction on the upper or cambered face of a suitably formed propeller may be greater in the region of slot 15 than it is in the region of slot 14. However, the centrifugal 25 force is relied upon primarily to achieve the result desired.

By removing air from the surface of the propeller blade at one region of its cambered face and ejecting it from another region thereof, the 30 thin film of air clinging to said surface is removed or energized, with the result that more efficient operation of the propeller is achieved.

In the embodiment of the invention shown in Figure 2, the cambered face of the propeller blade 11^a is formed with a slot 17 that is disposed in the aerofoil portion of the blade but relatively near the hub 10^a, said slot communicating with a duct 18 that is formed interiorly of the blade and extends longitudinally thereof for a substantial distance, said duct terminating in a discharge orifice 19 on the margin of the blade at the trailing edge thereof. In like manner a second slot 20 is formed in the same face of the blade, relatively near the tip thereof, said slot communicating with a duct 21 that terminates in a discharge orifice 22 on the trailing edge of the blade.

Centrifugal force set up in the air in ducts 18, 21 during rotation of the propeller causes said air to be ejected from the blade through orifices 19, 22, and concurrently air is drawn into the ducts, by suction, through the respective surface slots 17 and 20. Discharge of the air at the trailing edge of the blade performs the useful function of assisting in the propulsion of the blade by reducing the torque of the motor that drives the propeller.

In the embodiment of the invention shown in Figure 3, the propeller blades 11^b are each formed a plurality of parallel, longitudinally extending, internal ducts 24, 24, the inner ends of which terminate in respective slots 25, 25 that open onto the cambered face of the blade, said slots 25 being arranged in a row longitudinally of the blade. At their outer ends the ducts 24 terminate on the margin of the blade at the tip thereof in delivery orifices 26, 26, the latter being somewhat flared as shown, to diffuse the air ejected therefrom.

In the embodiment of the invention shown in Figure 4, each of the blades 11^c of the propeller is formed in its cambered face with a slot 28 disposed in the aerofoil portion of the blade relatively near the hub 10^c, and a slot 29 disposed relatively near the tip of the blade.

Formed interiorly of the blade 11^c is a relatively short, longitudinally disposed duct 30^a that extends radially inwardly from the slot 28 to a valve 31 that is located close to the hub 10^c, and a relatively long, longitudinally extending 5 duct 30^b that extends from the valve 31 to the slot 29. The valve 31 is an automatically operating check valve that is yieldingly urged by a compression spring 32 onto a valve seat 33, said valve being slidably mounted upon a headed 10 stem 34 carried by a body member 35 that is threaded into the structure of the blade. The spring 32 is of proper strength to permit the valve to open automatically when there is determinate differential fluid pressure in the ducts 15 30^a, 30^b, which differential pressure is established when the rotation or the working condition of the propeller reaches a determinate condition. When the valve is open, ducts 30^a, 30^b are in communication and air is drawn into the 20 ducts through slot 28 and ejected therefrom through slot 29 in the manner of the embodiment shown in Figure 1. The valve 31 is positioned as close to the hub 10^c as possible so as not to be materially influenced by the rotation 25 of the propeller.

The embodiment of the invention shown in Figure 6 is substantially similar to that shown in Figure 4 except that its valve is arranged for manual operation. As shown in Figure 6, 30 the propeller blade 11^d is formed with surface slots 37, 38 that communicate with the outer ends of interiorly disposed ducts 39^a, 39^b, the latter terminating at their inner ends on opposite sides of a check valve 40 mounted in the blade adjacent the hub 10^d of the propeller. As shown in Figure 7, the valve 40 engages a valve seat 41, and is carried upon the end of the core 42 of a solenoid 43, the latter being mounted in a suitable recess in the blade and being retained 40 therein by a threaded cap 44. A compression spring 45 is mounted between the valve 40 and the adjacent end of the solenoid, said spring normally urging the valve into seating engagement with the seat 41. For operating said solenoid, a pair of conductor wires 46 are provided, which wires extend through a duct 47, formed axially of the propeller hub 10^d, to a suitable battery 48 and operating switch 49 disposed at a convenient point removed from the propeller. 50 The arrangement is such that an operator may open the valve 40 at will, and thus permit the slots 37, 38 and connecting ducts to function in the manner described.

The invention increases the efficiency of propeller blades, is simpler than means heretofore provided for achieving a similar function, and achieves the other advantages set out in the foregoing statement of objects.

Modification may be resorted to without departing from the spirit of the invention or the scope of the appended claims.

What is claimed is:

1. A propeller of the character described comprising a blade having a major portion of aerofoil section and formed interiorly with a duct that extends longitudinally of the blade and radially of the axis of the propeller, the inlet end of said duct being nearest the axis of the propeller and opening onto one region of the aerofoil portion of the blade on the cambered side thereof, removed from the leading edge thereof to avoid scoop effect, and the delivery end of the duct opening onto another region of the aerofoil portion of the blade more remote from 65 70 75

the axis of the propeller, and so constructed and arranged that rotation of the propeller effects a flow of fluid in the duct, which fluid enters one end of the duct and discharges from the other end thereof for energizing the layer of the same fluid on the surface of the blade, the duct openings being relatively small so as not materially to reduce the effective area of the blade.

2. A combination as defined in claim 1 in which the delivery end of the duct opens onto the cambered face of the blade.

3. A combination as defined in claim 1 in which the delivery end of the duct opens onto a margin of the blade.

4. A combination as defined in claim 1 in which the delivery end of the duct opens onto the tip of the blade.

5. A combination as defined in claim 1 in which the delivery end of the duct opens onto the trailing edge of the blade.

6. A propeller of the character described comprising a blade formed interiorly with a duct that has its respective ends opening onto the surface of the blade at spaced apart points thereon, and so arranged that rotation of the propeller effects a flow of fluid longitudinally in said duct, and means for obstructing the flow of fluid in said duct until the pressure difference between the two openings of the duct reaches a determinate value.

7. A propeller of the character described comprising a blade formed interiorly with a duct, the ends of which open onto the surface of the blade at spaced apart points thereon, and so arranged that rotation of the propeller effects a flow of fluid longitudinally in said duct, and a check valve in said duct operated automatically by differential fluid pressure on opposite sides thereof.

8. A propeller of the character described comprising a blade having a major portion of aerofoil section and formed interiorly with a duct, the respective ends of which open onto the surface of the blade at spaced apart points of said aerofoil portion thereof, and so arranged that rotation of the propeller effects a flow of fluid longitudinally in said duct, a check valve adapted to obstruct the flow of fluid in said duct, and means for manually controlling the operation of the check valve from a point removed from the propeller, said means comprising a solenoid in the blade, and electrical conductor wires extending axially through the hub of the propeller for conducting operating current to the solenoid.

9. A propeller of the character described comprising a blade having a major portion of aerofoil section, and formed interiorly with a longitudinally extending duct of which one end ter-

minates in a slot in the cambered face of the blade in the said aerofoil portion thereof, and the other end terminates in a flared orifice on the margin of the blade to effect diffusion of fluid ejected therefrom by reason of the rotation of the propeller.

10. A propeller of the character described comprising a blade having a major portion of aerofoil section, and means for withdrawing fluid into the blade from the surface of the cambered side of said aerofoil portion, removed from the leading edge to avoid scoop effect, and expelling it from the blade on the same side of said aerofoil portion at a region removed from the point where it enters the blade, said means comprising openings in the blade of such small size as not materially to reduce the effective area of the blade.

11. A propeller of the character described comprising a blade having a major portion of aerofoil section, and formed interiorly with a longitudinally extending duct that has its ends opening onto the surface of the blade at spaced apart points of said aerofoil region, the inlet end of said duct, at least, being located on the cambered side of said blade, said duct being so arranged that rotation of the propeller effects a longitudinal flow of fluid therein, and means located in said duct relatively close to the hub of the propeller for regulating the flow of fluid in the duct.

12. A propeller of the character described comprising a blade having a major portion of aerofoil section, means for removing air locally from the surface of the blade, in the said aerofoil region, solely by suction as the propeller rotates, and a duct in said blade having a discharge orifice at the surface thereof for discharging said air from the blade, said orifice being so located in the aerofoil region of the blade and so shaped as to reduce losses in the efficiency of the propeller due to the energy of the discharging fluid.

13. A propeller of the character described comprising a blade having a major portion of aerofoil section formed interiorly with a curvilinear duct, the respective ends of which open onto the surface of the blade at spaced apart points longitudinally of said aerofoil portion, and so arranged that centrifugal force set up by rotation of the blade effects a flow of fluid longitudinally of the duct, an intermediate portion of said duct being disposed nearer the hub of the propeller than the inlet or outlet of the duct, and means located in the aforesaid intermediate portion of the duct for regulating the flow of fluid therein.
